FRINGE.

No. 15,584

Patented Dec. 2, 1884.

UNITED STATES PATENT OFFICE.

HENRY GOLDTHORP, OF PHILADELPHIA, PENNSYLVANIA, ASSIGNOR TO
EDWARD H. GODSHALK, OF SAME PLACE.

DESIGN FOR FRINGE.

SPECIFICATION forming part of Design No. 15,584, dated December 2, 1884.

Application filed September 11, 1884. Term of patent 34 years.

To all whom it may concern:

Be it known that I, HENRY GOLDTHORP, a citizen of the United States, residing in the city and county of Philadelphia, State of Pennsylvania, have invented and produced a new and original Design for Fringe, of which the following is a specification, reference being had to the accompanying photographic illustration, forming part thereof.

10 The leading feature of my design for a fringe is a pendant with a tuft ornamenting the top or bottom, or both, of the same, said pendant having two series of faces, each face being of pentagonal form, the faces of one series being

15 in reverse order to those of the other series.

A represents a fringe consisting of a pendant, a, a suitable heading, b, and a tuft, c, at the top or bottom end, or both, of said pend-

ant. The pendant has on its face two series of faces—one at the top and the other at the bottom—each face being of pentagonal form, the series being in reverse order and joining with a zigzag line around the pendant, and the faces of one series alternate with those of the other series, the whole producing an attractive design.

I claim—

A design for fringe, consisting of a heading, a pendant, and a tuft, said pendant having two series of faces of pentagonal form and in reverse order, and said tuft being on the end of the pendant, as shown and described.

HENRY GOLDTHORP.
